MAGNETIC DEVICE

Talmage D. Thomas, Dallas, Tex.

Application April 9, 1938, Serial No. 201,084

3 Claims. (Cl. 175—367)

This invention relates to new and useful improvements in magnetic devices.

One object of the invention is to provide an improved device which may be moved over the floor for picking up all of the metallic objects capable of being attracted by a magnet, and being particularly adapted for use in beauty parlors, or similar establishments for recovering hairpins, or similar objects which have been accidentally dropped by the operators.

An important object of the invention is to provide an improved magnetic device which has means for creating and setting up a magnetic force, whereby metallic objects may be attracted and held thereby; said means being so constructed that the magnetic force may be removed when desired, so that the metallic objects held thereby may be readily released and will fall from their held position by gravity, whereby the necessity of pulling the objects from the magnet, as is the case where permanent magnets are employed, is eliminated.

Another object of the invention is to provide an improved device, of the character described, wherein an electrically operated coil is utilized to set up a magnetic field which attracts the metallic objects in proximity thereto; said objects being retained so long as electrical current flows through the coil and being automatically and immediately released when the flow of current to the coil is cut off.

Still another object of the invention is to provide an improved device which is readily movable over the floor, or other surface and which has a receiving chamber therein, said chamber being constructed of non-magnetic material and having an electrical coil surrounding the same whereby when said coil is energized, a magnetic field is set up or created within the chamber so as to attract metallic objects thereto; the size of the chamber and the coil being so constructed that the proper magnetic force, without danger of overheating said coil, is produced.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is an isometric view of a magnetic device, constructed in accordance with the invention.

Figure 2 is a longitudinal, sectional view thereof.

Figure 3 is a transverse, vertical, sectional view, taken on the line 3—3 of Figure 2, and

Figure 4 is a reduced horizontal, cross-sectional view, taken on the line 4—4 of Figure 2.

In the drawing, the numeral 10 designates a flat base plate, or support, which is constructed of a non-magnetic material, such as "Bakelite", wood, or the like. The plate is shown as having a general rectangular shape, but the size and shape of the same is subject to variation. A longitudinal shaft or axle 11 is secured to the underside of the base by bearing collars 12, or other means and the ends of said axle project beyond the ends of the base. A supporting wheel 13 is rotatably mounted on each projecting end of the axle, being confined between suitable washers 14. A cotter key 15, or other removable element, holds each wheel on the axle and, obviously, the base plate 10 is supported on the wheels 13, whereby it may be readily moved over a floor, or other surface. If desired, the cotter keys 15 may be replaced by nuts (not shown) which would thread on the ends of the axle to hold the wheels thereon and yet permit ready removal of said wheels for cleaning, oiling, or other purposes. The axle 11, collars 12, washers 14 and wheels are constructed of non-magnetic material, it being desirable to make the metallic parts of brass, or similar non-magnetic metal, while the wheels may be of wood, hard rubber, Bakelite, or other suitable material.

An opening 16 is provided in the base plate and is preferably located at the central portion thereof. The opening is illustrated as rectangular in shape but, as will be explained, it may vary in shape and size. A collar or housing 17 having vertical walls, and being rectangular in cross-section, surrounds the opening and extends upwardly therefrom, whereby a receiving chamber A is formed above the opening 16. The chamber is constructed of a non-magnetic material and may, if desired, be made integral with the base.

The housing 17 and base plate 10 are covered by an outer casing or hood 18 which encloses these parts. The top of the casing or hood rests upon the upper end of the collar or housing 17, while its side walls overlie the edges of the base plate so as to completely enclose the plate and collar. The lower edges of the end walls of the casing are recessed at 17' to receive the axle 11. The casing or hood may be secured to the plate in any suitable manner, as by non-magnetic screws 19 (Figure 2) and an upwardly inclined

handle 20 extends upwardly from the top of the casing. The handle may be made integral with the casing and facilitates moving the device along the floor, or other surface, on its wheels 13.

5 For attracting metallic objects, capable of attraction by a magnet, an electrical coil or winding B surrounds the collar or housing 17. The coil is formed by winding wire around said housing, or collar, and is supplied with current by an 10 electrical lead wire 21 which extends downwardly through the handle 20. A suitable switch 22 is mounted in the handle, whereby the operator may readily control the flow of current to the coil.

15 When the coil B is energized a magnetic field is set up within the chamber A and as the device is moved over the floor, or other surface, the magnetic force of said field attracts the metallic objects on the surface and pulls them upwardly 20 into the chamber, whereby said objects adhere to the wall of the collar or housing 17 (Figure 2).

As long as the current is flowing through the coil, the metallic objects are held against said wall and are retained within the chamber A. 25 Therefore, by energizing the coil and moving the device over a floor, or other surface, the metallic objects on such surface may be readily picked up and retained in the chamber.

After the objects are within the chamber A, 30 the device may be placed over a box, or container, in which the objects are to be deposited and the current flowing to the coil is then cut off to de-energize the coil B. As soon as this occurs, the magnetic field and the magnetic force 35 created thereby, are removed, whereby the metallic objects may fall, by gravity, from the chamber. Since the housing 17, as well as the other parts of the device, are constructed of a non-magnetic material, there is no danger of these parts becoming 40 magnetized, or retaining a residual magnetism which would prevent the metallic objects from falling from the chamber A. From the foregoing, it is manifest that the metallic objects are retained and held within the chamber A 45 until the electrical current to the coil B is cut off, after which said objects are released. The release of the objects in this manner is accomplished automatically by gravity and eliminates the necessity of pulling the objects from the 50 device, as is the case when a permanent magnet is employed.

The size and shape of the chamber A may be varied as desired, but since the chamber forms an air gap, or space within the coil B, said coil 55 will vary as the size of the chamber is varied. It is well known that the magnetic force created by a magnetic field is dependent upon the product of the number of turns of wire times the number of amperes flowing through said wire and, therefore, when the size of the chamber is varied the 60 length of wire in the coil must be changed accordingly. If the same amount and size of wire were used, with the same amperage and a smaller chamber, a greater number of turns would be 65 had, with the result that a greater magnetic force would be set up. If the same wire were applied to a larger chamber, the number of turns

would be decreased, thereby decreasing the magnetic force. Therefore, the air gap formed by the chamber A, bears a definite relationship to the coil which must be of such construction that it will set up a sufficient magnetic force without overheating. Overheating of the wire forming the coil is caused by a flow of current in excess of the normal capacity of the wire and, therefore, it is desirable that the length of the wire, as well as the size thereof, be such that it will carry 10 sufficient current to set up the desired magnetic force without overheating.

15 The device is particularly adapted for use in beauty parlors where it is desirable to recover hairpins, bobby pins, and the like, which have 20 been accidentally dropped. However, it may be employed wherever it is desired to pick up metallic objects. Further, the invention is not to be limited in size, shape, or portability as it may be made larger to pick up heavier articles, capable 25 of being attracted by a magnet.

25 The foregoing description of the invention is explanatory of the same and various changes in the size, shape and materials, as well as in the details of the illustrated construction may be 30 made, within the scope of the appended claims, without departing from the spirit of the invention.

What I claim and desire to secure by Letters Patent is:

30 1. A device for picking up loose objects of magnetic material distributed over a floor or other surface, including a receiving receptacle, and electromagnetic means surrounding the same, 35 rollers mounted thereon and engaging the surface for supporting the electromagnetic means and receptacle directed downward at a substantially fixed distance over and adjacent to the surface, means for connecting the electromagnetic means with an electric power supply, and 40 means for moving the device over the surface whereby the magnetic objects may be removed therefrom and lodged in said receiving receptacle.

45 2. A device for picking up loose magnetic objects in accordance with claim 1 wherein the receiving receptacle is formed of non-magnetic material whereby magnetic objects regardless of how small they may be will be retained therein only so long as the surrounding electromagnetic means is energized.

50 3. A device for picking up loose objects of magnetic material distributed over a floor or other surface, including a casing having a receiving chamber therein, rollers mounted on said casing movable supporting the same over a surface with 55 said receiving chamber directed toward the surface, an upwardly directed handle connected with said casing for manually moving the same over a floor or other surface, a magnetizing coil within the casing and surrounding the chamber, and means for connecting said coil with an electric power supply for energizing the same for picking up the magnetic objects from the surface and retaining them in the receiving chamber as the device is moved over the surface. 60 65
